UNITED STATES PATENT OFFICE

136,737

DESIGN FOR A CLOTHESPIN

Walter R. J. WOOCK, Auburn, Calif.

Application August 12, 1934, Serial No. 110,895

Term of patent 14 years

To all whom it may concern:

Be it known that I, Walter R. J. WOOCK, a citizen of the United States of America, residing at Auburn, in the county of Placer and the State of California, have invented a new, original, and ornamental Design for a Clothespin, of which the following is a specification, reference being had to the accompanying drawing, forming part thereof.

I claim:

The ornamental design for a clothespin, as shown.

WALTER R. J. WOOCK.
